UNITED STATES PATENT OFFICE.

FRANK Z. HUSAR, OF CHICAGO, ILLINOIS.

ABDOMINAL SUPPORTER.

1,076,287.

Specification of Letters Patent. Patented Oct. 21, 1913.

Application filed May 10, 1913. Serial No. 766,675.

To all whom it may concern:

Be it known that I, FRANK Z. HUSAR, a former subject of the Emperor of Austria-Hungary, who have declared my intention 5 of becoming a citizen of the United States, and a resident of the city of Chicago, county of Cook, and State of Illinois, have invented certain new and useful Improvements in Abdominal Supporters, of which the following is a specification.

10 My invention relates to abdominal supporters and the object of my improvement is the production of a device of the character mentioned which presents a soft yielding surface to the skin of the wearer, has independent adjustable "lift-up" straps across its face and provided with thigh straps at its lower edge.

Other objects will appear hereinafter.

15 The invention consists in the combinations and arrangements of parts hereinafter described and claimed.

The invention will be best understood by reference to the accompanying drawing 20 forming a part of this specification, and in which—

25 Figure 1 is a front view of a device embodying my invention and indicating it in position on a wearer, Fig. 2 is a back view 30 of the same, and Fig. 3 is a section taken on line 3—3 of Fig. 2, with the device positioned in circular form.

The preferred form of construction as 35 illustrated in the drawing comprises a soft flexible band 4, of any suitable material such as knitted fabric, tricot cloth, or the like, open at the back and having ends 5 of non-yielding fabric, or other material secured thereto. The ends 5 are connected by 40 a lacing 6 laced in perforations 7 therein and a soft flexible tongue 7' is secured to one end 5 and extended under the lacing 6 to present a soft surface to the wearer.

Disposed on the outer surface of the band 45 4 are a plurality of elongated sheets 8 of yielding non-elastic material, secured at their central portions to the front of said band 4 by stitchings 9. Any desired number of elongated sheets 8 may be used and 50 disposed across the width of the band 4. A reinforcement 10 is provided at each end of each elongated sheet 8 and carries a buckle 11, which forms an adjustable lock for the front end of a strap 12. The straps 55 12 are secured at their rear ends to the end portions 5 by stitchings 13 and are of either

elastic or non-elastic web or other suitable material.

Two reinforcing sheets 14 are secured to the lower edge of the band 4 at its front 60 side and each sheet 14 carries a buckle 15 and a button 16. Buttoned on each of said buttons is a thigh strap 17 which is adapted to pass around the upper portion of the leg of the wearer and engage a buckle 15 to 65 hold the band in position.

The device is particularly adapted for use of persons recovering from abdominal operations and during gestation. It is placed in position on the wearer and lacing 6 adjusted to give the belt proper size. The thigh straps 17 are secured to the belt 4 at its lower front edge substantially as indicated and in position to hold said front edge over the lower portions of the abdomen and 70 in the groin of the wearer. The "lift-up" straps, comprising elongated sheets 8, straps or webs 12 and their connections, are then each independently adjusted to support the desired portion of the abdomen. 75

With the use of independently formed and adjustable "lift-up" straps, any desired portions of the abdomen may be supported and other portions freed, or some portions of the abdomen may be given more 80 support than others such as affording little or no pressure on a wound and firmly supporting other portions of the abdomen when so desired. The soft band 4 provides a cushion for the more firm portions secured 85 on its outer surface and permits of freedom of movement with comfort to the wearer. The thigh straps prevent upward movement and displacement of the device. With devices on the market it is difficult to give 90 proper support to the lowermost portions of the abdomen but with my device as described this is satisfactorily accomplished. 95

While I have illustrated and described the preferred form of construction for carrying 100 my invention into effect, this is capable of variation and modification without departing from the spirit of the invention. I, therefore, do not wish to be limited to the precise details of construction set forth, but desire 105 to avail myself of such variations and modifications as come within the scope of the appended claims.

Having described my invention what I claim as new and desire to secure by Letters 110 Patent is:

1. A device of the kind described com-

prising soft flexible band; firm end portions secured to said soft flexible band; a lacing connecting said firm end portions; spaced non-elastic members extending longitudinally on and stitched to said soft flexible band only at their central portions; and straps stitched to said firm end portions and adjustably secured to the ends of said non-elastic members, substantially as described.

- 10 2. A device of the kind described comprising soft flexible band; firm end portions secured to said soft flexible band; a lacing connecting said firm end portions; spaced non-elastic members extending longitudinally on and stitched to said soft flexible band only at their central portions; straps stitched to said firm end portions and ad-

justably secured to the ends of said non-elastic members; two spaced reinforcing sheets secured to the lower front edge portion of said soft flexible band; a button on one end of each reinforcing sheet; a buckle on the other end of each reinforcing sheet; and a thigh strap engaging the buckle and button on each reinforcing sheet, substantially as described.

20 In testimony whereof I have signed my name to this specification in the presence of two subscribing witnesses.

FRANK Z. HUSAR.
